CLAIM

We claim the ornamental design for a satellite speaker, as shown and described.

DESCRIPTION

FIG. 1 shows a first perspective view of the satellite speaker; FIG. 2 shows a second perspective view of the satellite speaker

FIG. 3 shows a front view of the satellite speaker;

FIG. 4 shows a rear view of the satellite speaker;

FIG. 5 shows a first side view of the satellite speaker;

FIG. 6 shows a second side view of the satellite speaker;

FIG. 7 shows a top view of the satellite speaker; and,

FIG. 8 shows a bottom view of the satellite speaker.

The portions shown in broken lines form no part of the claimed design.
